UNITED STATES PATENT OFFICE.

GEORGE ROBERT YOUNG, OF HUNTINGTON, NEW YORK, ASSIGNOR, BY MESNE ASSIGNMENTS, TO YOUNG SAND AND GRAVEL CORPORATION, OF NEW YORK, N. Y., A CORPORATION OF NEW YORK.

APPARATUS FOR SEPARATING SAND.

Application filed October 17, 1919, Serial No. 331,439. Renewed July 18, 1923.

To all whom it may concern:

Be it known that I, GEORGE ROBERT YOUNG, a subject of the British Empire (who has declared his intention of becoming a citizen of the United States), residing at Huntington, county of Suffolk, and State of New York, have invented a certain new and useful Apparatus for Separating Sand, of which the following is a specification.

10 This invention is a separating apparatus, the same being useful, more particularly, in mechanically and hydraulically separating gravel, sand and grit one from the other in order to attain economy of time and 15 labor in the treatment of such natural materials and thereby render the same marketable as products.

According to this invention, the flow of a liquid current is utilized in connection with 20 a mechanical screen to preliminarily effect the separation of the sand and grit from the gravel or analogous mineral aggregate, and as a continuous step in the treatment of the separated material, the sand is there- 25 after separated from the grit by the action of a second mechanical screen in conjunction with the flow of a liquid current. As a result of the separating and washing processes, gravel, grit and sand are rapidly 30 and economically separated one from the other, such separated materials are accumulated in independent masses, suitable means being provided whereby the materials are independently carried to appropriate 35 receptacles or other desired places of deposit whence the separated masses may be distributed as found desirable.

Other functions and advantages of the invention will appear from the following 40 description taken in connection with the drawings, wherein—

Fig. 1 is a view partly in side elevation and partly in longitudinal section of a separating apparatus embodying the invention.

Fig. 2 is a vertical cross section partly in end elevation, the plane of the section being indicated by the irregular dotted line 2—2 of Fig. 1.

Fig. 3 is a vertical cross section partly in end elevation, the plane of the section being on the line 3—3 of Fig. 1.

In carrying my invention into practice means are provided whereby water is caused to flow at slow speed within a definite channel, said means being either a natural water

course or an artificial channel. In Fig. 1 of the drawings the water course A is shown as having an artificial bottom a composed usually of hydraulic cement. The continuity of this water channel, at least so far as concerns the bottom a thereof, is interrupted by the provision of a chamber B, the walls b and the bottom b' of which are artificially created by excavating the material and by the establishment of concrete walls and the bottom. It is essential that said chamber B shall be in communication with the water channel, and further that the bottom b' of the chamber shall be in a plane below the bottom a of the water course.

Positioned in cooperative relation to the water course or channel A is a screening mechanism, the under surface of which extends below the normal level of the water 75 adapted to flow within the channel A, whereby the water is adapted to flow through or within the screen for the purpose of washing sand and grit from the gravel under treatment within the screening mechanism. It is preferred to employ a rotary tapering screen C, the under surface of which screen is inclined at an angle to the normal level of the water within the channel A. Said screen is composed of a desirable number of metal hoops or bands c, a metal band c' at the feeding end of the cylinder, an imperforate head c² at the delivery end of the screen, and foraminous or perforated material c³ attached to the bands c, the feed member c' and the delivery member c². Preferably, the perforated members c³ are composed of wire material, the mesh of which is of such size that the gravel present in the material under treatment will 80 be retained within the screen, whereas the sand and fine grit will be carried by flotation with the water, a salient feature of the invention being that the flow of water within the screen C acts to wash the sand and grit from the gravel and to perform the additional function of carrying the sand and gravel through and away from the screen C, whereby the sand and grit may by a subsequent treatment be separated so that 85 the sand is collected in one mass, whereas the grit is collected in a separate receiver, as will presently appear.

The rotary tapering screen C may obviously be of any desired size and capacity, 110

and it is carried by a shaft D, the end portions of which protrude beyond the cylinder so that the shaft is adapted to be mounted in appropriate bearings d d attached to 5 supporting rails d' of a suitable framework. Means are provided for imparting rotary motion to the shaft and the screen, said driving means being illustrated in the form of a gear d^2 adapted to mesh with a gear 10 pinion d^3 on a horizontal shaft D' , the latter being supported in suitable bearings d^4 and being driven by a sprocket and chain gearing d^5 , all as shown in Fig. 1.

The material to be treated is obtained 15 from any source of supply, said material consisting of gravel, sand and grit adapted to be transported from its place of natural deposit to the treating apparatus. Means are provided for automatically feeding said 20 material into the screen C. As herein shown, the feed means is a hopper E having a spout e which is inclined so as to extend into the imperforate section c' of the screen, whereby the material flows by gravity into the small 25 end of the screen. The rotation of the screen subjects the material to agitation, and the under surface of the tapering screen being inclined in an opposite direction to the direction of flow of the water within 30 the channel A, effects the gravity feed of the material within the screen and in an opposite direction to the flow of water through the screen and within the channel. The agitation and gravity feed of the material 35 results in the collection of the gravel within the member c^2 at the larger end of the screen, whereas the circulation of water through the screen washes the sand and grit from the gravel by flotation, and thus 40 sand and grit are carried out of the screen with the water and along the channel or course A in the direction indicated by the arrows in Fig. 1.

Means are provided for automatically dis- 45 charging the gravel collected within the member c^2 at the larger end of the screen, said collecting and discharging means being shown more particularly in Figs. 1 and 3 of the drawings. The member c^2 of the screen 50 is provided with an inwardly extending flange f constituting an annular head or ring at the delivery end of the screen. Secured within the member c^2 and its head f is a series of buckets f' , the same being shown 55 in the form of plates fixed to the member c^2 on the inner surface thereof and extending tangentially to the circular outline of said member. Extending into the member c^2 of the screen is a hopper F positioned in 60 cooperative relation to the buckets f' , whereby the gravel elevated by the buckets f' upon the rotation of the screen C is deposited within said hopper F. The bottom f^2 of the hopper is open for the free exit 65 of the gravel deposited therein, see Fig. 3,

and below this open end of the hopper is an off-bearing carrier G, herein shown as a belt passing around a belt wheel or pulley g mounted on the screen shaft D, whereby the gravel collected in the hopper F is deposited upon the off-bearing carrier G so that the gravel will be transported away from the hydraulic separating apparatus and be collected or accumulated in a pit or gravel bank, whence the gravel may be 75 transported as desired.

From the foregoing description it will be understood that the gravel is preliminarily separated from the sand and grit by the hydraulic action of the water and by the 80 mechanical operation of the first screen C, and thereafter the sand and grit are carried by flotation to a second screening mechanism wherein the sand and grit are mechanically separated one from the other and subjected 85 to hydraulic action so that the fine particles of sand may be discharged separately from the grit.

The second screen referred to is shown as a tapering rotatable screen H which in a 90 preferred form is considerably shorter and of greater diameter than the primary separating screen C. Said second screen is composed of one or a suitable number of bands h , a delivery member h' , and a suitable 95 number of perforated members h^2 . The perforated members h^2 are composed of foraminous or perforated material, preferably wire material, the meshes of which are of such size as to retain the gritty material, 100 whereas the finer particles of sand are permitted to pass through the openings of said screen material. The second screen H is carried by a shaft H' journaled in bearings i attached to suitable rails i' . Said second 105 screen is positioned over the collecting chamber B, the length of the screen being somewhat less than the width of the chamber. Furthermore, the second screen is arranged for its under surface to extend well 110 below the normal level of the water flowing within the channel A and over the chamber B, and, further, the receiving end of the screen H is adjacent the bed a of the water course. It will be recalled that the screen C 115 has an under surface inclined in one direction to the normal level of the water within the course A, but the screen H is so related to the parts with which it co-acts that the under surface of said screen H is inclined 120 in an opposite direction to that of the corresponding surface of screen C, said under surface of the screen H being not only inclined to the normal level of the water, but inclined also to the bed a of the water 125 course so that said under surface of screen H extends in an inclined direction within the upper part of collecting chamber B, as clearly shown in Fig. 1. The relation of the screen H to the chamber B and to the 130

water course is such that the sand and grit carried by the water away from the screen C will flow into and be caught by the screen H, so that the sand and grit will be subjected to agitation by the rotary motion of said screen H and conjointly with this agitation the sand and grit are exposed to the hydraulic action of the water flowing within the course and over the chamber, thereby effectively separating the sand from the grit so that the sand will be accumulated within the chamber B, the bottom b' of which is in a plane below the bed a of the water course. Owing to the specific gravity of the sand and grit carried by the flow of water within screen C, said sand and grit will be precipitated upon the bed a of the water course, along which the sand and grit will be carried by the flow of water, but in this connection it will be noted that the under surface of the partially submerged screen H is in a plane below and inclined at an angle to the bed a of the water course, and, further, that the receiving end of the screen H is in close proximity to said bed a whereby the sand and grit will be carried into the screen H by the flow of water within the course.

Separate means are provided for discharging the grit collected by the screen H and for discharging from the chamber B the sand accumulated therein. The gritty material agitated by the rotary motion of the screen is retained by the mesh of said screen so that it will pass into the imperforate section h' at the large delivery end of screen H, said delivery section h' being provided with an inwardly extending flange j constituting an annular head for the screen H, see Figs. 1 and 2. Secured within the imperforate section h' of the second screen is a series of buckets j' , shown in Fig. 2 as flat plates attached to the section h' so as to lie tangentially thereto. Said buckets are adapted by the rotary motion of the screen to carry the gritty material to the upper part of the screen whence the material is discharged into a hopper I, the latter being secured by suitable means in fixed relation to the screen so that the hopper extends into the imperforate section h' of said screen. As in the case of the hopper F, said hopper I is provided with an opening z^2 in the bottom thereof, and beneath said open bottom hopper operates an off-bearing carrier J, shown in Fig. 2 as an endless belt passing around a pulley or belt wheel j' mounted on the shaft H' of the second screen. Suitable means are provided for imparting rotary motion to the second screen; as shown, the shaft H' of the second screen is in alinement with the shaft D of the first screen C, and the adjacent ends of the shafts D H' are united by a coupling j^3 so that the motion of the shaft D is communicated directly to the shaft H' for imparting the rotary motion to screen H.

The means for discharging the sand accumulated within the chamber B is shown in Fig. 2 as a bucket elevator K, the loading end of which is adjacent the bottom of chamber B so as to scoop up the sand accumulated therein. The bucket elevator may be of any desired character and dimensions, and as shown in Fig. 2 the delivery end of this elevator is over a hopper k below which operates an off-bearing carrier L, the latter being driven by a suitable pulley l on the shaft H' of the second screen, see Figs. 1 and 2.

The operation is as follows:—

Water in the required volume and at a desired speed flows within the channel or course and over the chamber B. Motion having been imparted to the screens C H, the material is fed through hopper E into screen C. The material is agitated by the rotary motion of the screen, and the coarser particles are fed by gravity down the inclined surface of said screen C, whereas the flow of water through screen C washes sand and grit from the gravel. The gravel is collected within member c^2 of screen and is carried by the buckets f' to be deposited in the hopper F, whence the gravel is carried by the conveyor G to the gravel bank. The sand and grit are carried by flotation along the course A, and said sand and grit pass into second screen H, wherein said materials are subjected to agitation and to the action of the water. The grit is separated mechanically by the screening action from the sand, said gritty material passing into the imperforate section h' of the screen and carried by the buckets j' to the hopper I, whence the gritty material is deposited upon the off-bearing conveyor J. The sand passes through the meshes of the second screen and accumulates within chamber B, whence the sand is removed by the action of the elevator K which deposits the material into the hopper k , whence the sand is carried by the conveyor L to a separate place of discharge.

It will be understood that the gravel and coarse materials are carried to one place of deposit, the gritty material is carried to another place of deposit, and the finer material and sand are carried to a still other place of deposit, the separation of the three materials one from the other being due to the screening action of the parts C H, and to the hydraulic action of the current of water whereby the material is handled and separated in an efficient and economical manner.

In a practical form of the apparatus, it is desirable to preclude the sand and grit carried by the current flowing within the channel from passing directly into the chamber or pit, and to this end I provide a baffle D^2 , shown in the drawing as a plate attached

to the bed of the channel or course. Said plate extends across the space intervening the end of the channel or course and the chamber, the said plate projecting into the 5 second screen and operating to direct the lower strata of sand and grit into said screen, whereby the baffle tends to contribute to the delivery of the sand and grit so as to insure that these materials will be subjected to a 10 second screening action.

In addition to the functions hereinbefore recited, the flow of water within the first screen acts to carry off any branches or roots of trees, or other foreign matter, that may 15 be present in the natural material when it is excavated and thereafter supplied to the first screen. It is to be observed that the inlet end of said first screen is below the normal water level flowing within the channel, and 20 that the water flows out of said inlet end. It has been observed that the natural material frequently contains dirt and more or less vegetable matter, such as the roots or branches of trees. Ordinarily, the hydraulic separation of 25 gravel from the other materials is carried on under such conditions that the roots and vegetable matter remain in the gravel, reducing the value of the gravel as a marketable commodity. In my invention, however, 30 this condition is eliminated. The agitation of the natural material by the rotary motion of the first screen and the flow of water in one direction while the gravel travels in a contrary direction, tends to free the 35 branches, roots and other vegetable matter from the gravel, as a result of which the branches, roots and vegetable matter will float on the surface of the water and thus be carried out of the first screen, through the 40 channel, and also through the second screen, whereby the vegetable matter is separated from the sand, gravel and grit so as to be discharged with the flowing water, and the gravel is delivered in a clean condition to a 45 point at one side of the water course, it being noted that the dirt is washed out of the gravel, sand and grit and floats away with the flowing water.

The process of separating gravel from 50 the sand and grit, and of separating the sand from the grit, herein disclosed, forms the subject matter of a separate application filed by me on even date herewith, Ser. No. 331,439.

Having thus fully described the invention, what I claim as new, and desire to secure by Letters Patent is:

1. A separating apparatus of the class described embodying screening mechanism the 60 operating surface of which is free from obstruction to the flow of a separating current and within which the material to be separated is subjected to agitation, and means whereby the flow of a liquid current 65 is established in such relation to said oper-

ating surface of said screening mechanism as to carry off by flotation the finer material from the coarser material under treatment.

2. A separating apparatus of the class described embodying means for establishing 70 the flow of a liquid in one direction, and screening mechanism partially submerged in the liquid and with the upper surface of said screening mechanism free from obstruction to the flow thereover of a separating 75 hydraulic current, said screening mechanism operating to effect the separation of coarse material from the finer material and the flow of the liquid tending to wash the finer material from the coarse material and by flotation to carry the finer material through and beyond the screening mechanism.

3. A separating apparatus of the class described embodying a rotatable screen, the inner surface of which is free from obstruction to the flow of a hydraulic current, means for feeding the material to be treated into said screen, and means for establishing the flow of a liquid current within the screen 80 and in a direction opposite to the path of said material within the screen.

4. A separating apparatus of the class described embodying means for establishing the flow of liquid in one direction, a rotatable screen partially submerged in said liquid, said screen having an inner surface free from obstruction to the flow of a hydraulic current and said screen presenting an inclined surface to the direction of movement of the liquid, whereby the material under treatment is adapted to gravitate in a direction opposite to the flow of the liquid, and means for feeding material to be treated 100 into said screen.

5. A separating apparatus of the class described embodying means wherein a liquid is adapted to flow in one direction, a rotatable screen partially submerged in said liquid, said screen having an inner surface free from obstruction to the flow of a hydraulic current and said screen being tapering to present a surface inclined to the direction of flow of the liquid within said screen, means for feeding the material to be treated into the screen, and means for collecting the coarse material separated by the screen from the finer material adapted by flotation to be carried out of the screen by 110 the flow of the liquid.

6. A separating apparatus of the class described embodying a water course wherein water is free to flow in one direction, a rotatable screen positioned for a part of its lower surface to extend below the normal water level within said course, the surface of said screen being free from obstruction to the flow of a hydraulic current and said screen surface being at an angle to the water line, means for feeding the material to 120

be treated into said screen, means for collecting and elevating the coarse material at one end portion of said screen, and an off-bearing carrier in cooperative relation to said collecting and elevating means.

7. A hydraulic separating apparatus of the class described embodying a water course wherein water is free to flow in one direction, a collecting chamber in communication with said water course, and a rotatable screen the inner surface of which is free from obstruction to the flow of a hydraulic current and the under surface of which is below the water level in said course, said screen occupying such relation to the water course that the material under treatment travels in a direction opposite to the flow of water within the screen whereby the material is washed and the finer particles of material are carried by flotation with the water from said screen and into said collecting chamber.

8. A hydraulic separating apparatus of the class described embodying a water course wherein water is free to flow in one direction, a collecting chamber in communication with said water course, a rotatable screen positioned over the water course and in such relation to the same that the under surface of the screen is substantially below the normal water level within the course, and a second rotatable screen positioned over the collecting chamber and with its under surface below the normal level of the water adapted to flow within the water course and the collecting chamber.

9. A hydraulic separating apparatus of the class described embodying a water course the bottom of which is interrupted by a collecting chamber, a rotatable screen positioned partially within the water course for the water to flow in one direction within said screen whereas the coarse material under treatment moves in an opposite direction within the screen, a second rotatable screen positioned over the collecting chamber and for its under surface to extend below the normal level of the water in said water course, and means for separately discharging the coarse material collected by the first screen and the finer material collected within said chamber.

10. A hydraulic separating apparatus of the class described embodying a water course provided with a collecting chamber the bottom of which is in a plane below the bottom of said water course, screening mechanism partially within the water course for the water to flow in one direction within the same, a second screening mechanism positioned over the collecting chamber and partially below the normal water level whereby the flow of water carries the finer material from the first screening mechanism to the second screening mechanism, means for

discharging coarse material collected by the first screening mechanism, and means for discharging finer material collected within said chamber.

11. A hydraulic separating apparatus of the class described embodying a water course provided with a collecting chamber the bottom of which is in a plane below the bottom of said water course, a tapering screen positioned for its lower surface to extend below the normal water level within said course, said under surface of the screen being in a plane inclined in one direction to the water level, and a second tapering screen positioned substantially over said collecting chamber and for its under surface to extend below the water level, said under surface of the second screen being in a plane inclined oppositely to the angle of inclination of the first screen. 85

12. A hydraulic separating apparatus of the class described embodying a water course provided with a collecting chamber the bottom of which is in a plane below the bottom of said water course, a tapering screen positioned for its lower surface to extend below the normal water level within said course, said under surface of the screen being in a plane inclined in one direction to the water level, a second tapering screen positioned substantially over said collecting chamber and for its under surface to extend below the water level, said under surface of the second screen being in a plane inclined oppositely to the angle of inclination of the first screen, means for collecting and discharging the coarse material collected by the first screen, and separate means for discharging the fine material collected in said chamber. 100

13. A hydraulic separating apparatus of the class described embodying a water course provided with a collecting chamber the bottom of which is in a plane below the bottom of said water course, a rotatable screen positioned over said course for the under surface of said screen to extend below the normal water level, a second screen over the collecting chamber and positioned for its under surface to lie in a plane substantially below the bottom of said water course, and means for discharging the materials collected by said first screen and said chamber. 110

14. A hydraulic separating apparatus of the class described embodying a water course provided with a collecting chamber the bottom of which is in a plane below the bottom of said water course, a rotatable screen positioned over said course for the under surface of said screen to extend below the normal water level, a second screen positioned over the collecting chamber for the receiving end of said screen to be adjacent the bottom of said water course, and 125

means for separately discharging the materials collected by said first screen and said chamber.

15. A hydraulic separating apparatus of the class described embodying a water course, a screen positioned for its under surface to extend below the normal level of the water in said course, a collecting chamber in communication with said water course, a second screen positioned adjacent the collecting chamber, said second screen

having means for collecting the grit separated from the sand by the conjoint action of the water and said second screen, and means for effecting the separate discharge of gravel collected by the first screen, the grit collected by the second screen, and the sand collected by said chamber. 15

In testimony whereof I have hereunto subscribed my name this 14th day of October, 1919.

GEORGE ROBERT YOUNG.
